DESIGN FOR A CHAIR

Thomas M. McDonald and Edward L. Monnot,
Canton, Ohio, assignors to The Weber Dental
Manufacturing Company, Canton, Ohio, a corporation of Ohio

Application April 14, 1938, Serial No. 76,488

Term of patent 7 years

To all whom it may concern:

Be it known that we, Thomas M. McDonald and Edward L. Monnot, both citizens of the United States, residing at Canton, in the county of Stark and State of Ohio, have invented a new, original, and ornamental Design for a Chair, of which the following is a specification, reference being had to the accompanying drawing forming part thereof.

Figure 1 is a perspective view of the chair, showing our new design, the chair parts being shown in one position of adjustment; and

The dominant features of the design are shown in full lines.

We claim:

The ornamental design for a chair, as shown and described.

THOMAS M. McDONALD.
EDWARD L. MONNOT.
